ABSTRACT OF THE DISCLOSURE

A function generator produces specified output signal magnitudes in response to specified input signal magnitudes. The generator includes a closed loop series regulator having a current sink in its feedback circuit.

BACKGROUND OF THE INVENTION

My invention relates to a function generator, and particularly to a function generator for producing an output signal having specified magnitudes for specified magnitudes of an input signal.

Many circuits require for control or operation, a signal or voltage which varies in magnitude in a predetermined fashion with respect to some other related factor or variable such as time, mechanical function or the like. Such signals or voltages are not always easily generated or supplied by simple or conventional circuits but may be obtained by modifying or converting the output signals of conventional generating circuits to signals which have the required characteristics or functions. Although the use of my invention is not limited to the following example, one such circuit is an oscillator whose frequency is to be varied or swept by changing the capacity in the oscillator tuning circuit. All or part of the capacity is provided by a varactor or diode whose capacity changes with applied voltage. Usually, the capacity of a varactor varies nonlinearly with the applied voltage, and where it is desirable that the oscillator frequency vary either linearly or in some other specified manner with respect to time or some other factor, a signal or voltage is required which will in turn cause the oscillator frequency to vary accordingly.

Accordingly, an object of my invention is to provide a signal that varies in a specified manner relative to an input signal.

Another object of my invention is to provide an improved function generator that converts an input signal into a specified output signal.

Another object of my invention is to provide a function generator that converts input signal magnitudes into output signal magnitudes having specified relationships or ratios for each set of input and output signals.

Operating conditions for a circuit, such as the oscillator mentioned above, may specify output voltages or signal magnitudes for selected or specified input voltages or signal magnitudes. Thus, the output signal must follow or track the input signal at specific points in a specified relation or manner.

Accordingly, another object of my invention is to provide a function generator that produces an output signal of a specific magnitude for each of a number of specific or selected points of the input signal irrespective of the magnitudes of the input signal before and after each specific point.

Another object of my invention is to provide an improved function generator for producing a signal that varies in a specified manner with respect to an input signal.

SUMMARY OF THE INVENTION

Briefly, these and other objects are achieved in accordance with my invention by a closed loop series regulator

2

circuit to which the input signal is applied and from which the output signal is derived. A current sink which absorbs or supplies specific and varying amounts of current is coupled to the feedback circuit of the closed loop series regulator circuit. The resultant voltage from the feedback circuit is compared with the input voltage to cause the series regulator to either increase or decrease the voltage at the output. Thus, the output voltage has the desired magnitude for each specific and selected magnitude of the input signal. The invention disclosed herein will operate satisfactorily with input signals which are either continuously variable or which are of a steady state nature, or which are of a random sequence combination of both.

BRIEF DESCRIPTION OF THE DRAWING

The subject matter which I regard as my invention is particularly pointed out and distinctly claimed in the claims. The structure and operation of my invention, together with further objects and advantages, may be better understood from the following description given in connection with the accompanying drawing, in which:

FIGURE 1 shows a table giving illustrative values of a typical input signal, illustrative values of an output signal for each value of the input signal, and other circuit parameters which explain the operation of my circuit;

FIGURE 2 shows a circuit diagram of my function generator with the current sink shown as a block diagram;

FIGURE 3 shows a circuit diagram of one embodiment of my current sink which may be used in the function generator of FIGURE 2; and

FIGURE 4 shows another embodiment of my current sink which may be used in the function generator of FIGURE 2.

DESCRIPTION OF THE PREFERRED EMBODIMENTS

With reference to FIGURE 1, Column 1 shows one set of the selected steps at which specified voltage magnitudes of an input voltage or signal V_{in} (Column 2) are to be converted to specified voltage magnitudes of an output signal V_o (Column 4). In Column 2, the input voltage V_{in} varies in a generally sawtooth fashion from -10 volts at Step 1 to zero volts at Step 14. However, it is to be understood that the input voltage may vary up and down, and that other magnitudes of the input voltage may be specified for the steps. Also, any number of steps may be specified. As shown in Column 4, the desired output voltage V_o varies from 20 volts to 110 volts with the indicated or specified magnitudes at each of the 14 steps. Thus, the input signal or voltage V_{in} shown in Column 2 must be converted to the output signal or voltages V_o shown in Column 4 for each of the specified steps. It is desirable that the transition of the output voltage V_o between each step be smooth so that the output voltage V_o varies in a smooth or nonerratic fashion. As mentioned previously, such an output voltage is desirable for various purposes such as varying the voltage across a varactor diode to change the frequency of an oscillator.

FIGURE 2 shows one embodiment of my function generator for converting or changing the input voltage V_{in} shown in Column 2 to the output voltage V_o in Column 6 at respective specified Steps 1 through 14 in FIGURE 1. My function generator includes a source 10 of direct current voltage V_1 which has a magnitude of 120 volts. The source 10 has its negative terminal connected to a reference bus 11 and its positive terminal connected to a positive bus 12. A second source 13 of direct current voltage V_2 having a magnitude of 17.75 volts is also provided.

The positive terminal of the source 13 is connected to the reference bus 11, and the negative terminal of the source 13 is connected to a negative bus 14.

The input voltage V_{in} relative to the reference bus 11 is applied to one input terminal of an error indicating circuit or differential type amplifier 18. The output of the amplifier 18 is coupled through a resistor 19 to the base electrode of an NPN type transistor Q_B . The emitter of the transistor Q_B is coupled to the negative bus 14, and the collector of the transistor Q_B is coupled through a resistor 20 to the base electrode of an NPN type transistor Q_A . The emitter of the transistor Q_A is coupled to the positive bus 12, and the emitter of the transistor Q_A is coupled to an output bus 21. The output voltage V_o is derived between the output bus 21 and the reference bus 11. A base-collector resistor 22 is also coupled to the transistor Q_A . The output bus 21 is coupled through a load resistor R_L to a summing point 25 which is coupled to the feedback input of the amplifier 18. A current I_L flows through the resistor R_L and produces a voltage drop V_L across the resistor R_L . A feedback voltage V_F is supplied between the summing point 25 and the reference bus 11. The amplifier 18 and the transistors Q_A and Q_B are coupled in an error measuring or closed loop series regulating circuit so that the feedback voltage V_F tends to track or follow the input voltage V_{in} . Hence, the voltages listed in Column 2 of FIGURE 1 represent both the input voltage V_{in} and the feedback voltage V_F . The summing point 25 is coupled to a current sink 26 which is constructed in accordance with my invention as will be described. The current sink 26 is also coupled to the reference bus 11 and the negative bus 14. The current sink 26 has a voltage drop V_{CS} across it as indicated in FIGURE 2.

As mentioned above, the feedback voltage V_F tracks or follows the input voltage V_{in} very closely, so that the two voltages have substantially the same magnitude. This is indicated in Column 2 of FIGURE 1. It will be understood, however, that there is actually a slight voltage difference between the two voltages V_F and V_{in} , depending on the circuit gain of the current regulating circuit. However, this slight difference may be ignored in the following description of the operation of my function generator shown in FIGURE 2. In FIGURE 2, the voltage across the current sink 26 is represented as the voltage V_{CS} , and this voltage is, as shown in Column 3, equal to the difference between the voltage V_2 of the source 13 and the feedback voltage V_F . By conventional circuit theory beginning at the reference bus 11, the voltage drop V_2 across the source 13, the voltage rise V_{CS} across the current sink 26, and the voltage rise V_F between the summing point 25 and the reference bus 11 are equal to zero. If these terms are transposed, the voltage V_{CS} across the current sink 26 is numerically equal to the voltage V_2 across the source 13 minus the feedback voltage V_F . Thus, at Step 1, the voltage V_{CS} is equal to 17.75 volts minus 10 volts, or 7.750 volts. The voltages V_{CS} for the other steps are similarly calculated. Column 5 of the table in FIGURE 1 shows the voltage V_L across the load resistor R_L . By conventional circuit theory beginning at the reference bus 11, the output voltage V_o rise, the voltage drop V_L across the resistor R_L , and the voltage rise V_F are equal to zero. If these terms are transposed, the voltage V_L is numerically equal to the feedback voltage V_F plus the output voltage V_o . Thus, at Step 1, the voltage V_L is equal to the feedback voltage V_F of 10 volts plus the output voltage V_o of 20 volts, or 30 volts. The other steps are similarly calculated. It has been assumed that the load resistor R_L has a magnitude of 10,000 ohms, and the current I_L through the resistor R_L for the various voltages is equal to the voltage V_L divided by this magnitude. Column 6 shows the current values in milliamperes for the Steps 1 through 14.

In order to provide the currents listed in Column 6 at the various steps and hence provide the output voltage V_o at the various steps, I provide the current sink 26 having a plurality of parallel current paths which take or absorb the various amounts of current listed in Col-

umn 6. FIGURE 3 shows the schematic or circuit diagram of the current sink 26. Since there are 14 specified steps, the current sink 26 theoretically comprises 14 NPN type transistors. But only three transistors Q_1 , Q_2 , and Q_{14} are shown in order to simplify the illustration of the circuit. The other transistors Q_3 through Q_{13} would be similarly connected into the circuit between the dashed line portions. The collector of each of the transistors is connected to the summing point 25, and the emitter of each of the transistors is connected through a respective resistor R to the negative bus 14. The base of each of the transistors is connected through a base resistor R_B to the movable contact of a potentiometer P . The potentiometer P of each transistor is connected between the reference bus 11 and the negative bus 14. In FIGURE 3, each of the transistors is indicated by the letter Q followed by a number, each of the emitter resistors is indicated by the letter R followed by a number, each of the base resistors is indicated by the letters R_B followed by a number, and each of the potentiometers is indicated by the letter P followed by a number. When any one of the transistors Q_1 through Q_{14} is carrying a saturation current, the voltage drop V_R across the respective one of the resistors R_1 through R_{14} is equal to the voltage V_{CS} (Column 3) across the current sink 26 minus the saturation voltage across the emitter and collector of the transistor. If this saturation voltage is assumed to be 0.2 volt for the transistors Q_1 through Q_{14} , then the voltage drop V_R for each of the steps has the value shown in Column 7. For example, at Step 1, the voltage V_R is 7.750 volts minus 0.2 volt, or 7.550 volts. The other voltages V_R are similarly calculated. The remainder of the columns of the table of FIGURE 1 indicate the step at which the voltage drop V_R across each one of the emitter resistors R saturates or limits the current through its respective transistor Q . In other words, these remaining columns indicate the point at which each of the parallel current paths limit the current therethrough. This limiting is determined by the setting of the movable contact on each of the respective potentiometers P . For example, at Step 1, when the input voltage V_{in} is at -10.000 volts and the current sink voltage V_{CS} is 7.750 volts, the potentiometer P_1 is set so that the transistor Q_1 passes no more current when the voltage V_R across its emitter resistor R_1 reaches 7.550 volts. If, after the voltage drop across the emitter resistor R_1 reaches 7.550 volts, the transistor Q_1 attempts to pass more current, it tends to bias itself off because of the setting of its potentiometer P_1 . Hence, when the transistor Q_1 passes a current that causes the voltage drop across the emitter resistor R_1 to reach a voltage of 7.550 volts, the transistor Q_1 passes no greater magnitude of current. As the input voltage V_{in} increases to -8.875 volts at Step 2, potentiometer P_2 is set so that the transistor Q_2 passes no more current when the voltage across its emitter resistor R_2 reaches 8.675 volts. The other potentiometers are set to provide the current limiting conditions for the other voltages indicated in Column 7. The columns or shaded areas in the remainder of the table of FIGURE 1 show the voltages at which the respective emitter resistors R and the potentiometers P limit the current magnitude in their respective transistors Q .

The values of the resistors R_1 through R_{14} were calculated as follows:

First, it was assumed that $X = A + B + C + D + \dots + N$, where $A = 1/R_1$, $B = 1/R_2$, $C = 1/R_3$, $\dots$, $N = 1/R_{14}$. For Step 1, the following equation was written:

$$7.550(X) = 3.0000$$

where X is defined as above, where 7.550 is the voltage drop V_R at Step 1, and 3.0000 is the current in milliamperes at Step 1. For Step 2, the following equation was written:

$$7.550(A) + 8.675(X - A) = 3.3875$$

For Step 3, the following was written:

$$7.550(A) + 8.675(B) + 9.800(X - A - B) = 3.7750$$

Similar equations were written for Steps 4 through 14. These 14 equations were solved, and the following values in ohms were found for the emitter resistors:

$R_1 = 18,901$	$R_8 = 5,000$
$R_2 = 0.14062 \times 10^{11}$	$R_9 = -5,000$
$R_3 = -4,499$	$R_{10} = -2,999$
$R_4 = 0.75000 \times 10^{10}$	$R_{11} = 0.99999 \times 10^{49}$
$R_5 = 0.99999 \times 10^{49}$	$R_{12} = 0.99999 \times 10^{49}$
$R_6 = -2,999$	$R_{13} = -3,749$
$R_7 = 0.16666 \times 10^{10}$	$R_{14} = 666$

In the above table, it will be noted that resistors R_3 , R_6 , R_9 , R_{10} , and R_{13} have negative values. This has been assumed to mean that their respective transistors Q_3 , Q_6 , Q_9 , Q_{10} , and Q_{13} supply current toward the summing point 25 rather than away from the summing point 25. The transistors connected in the current sink 26 shown in FIGURE 3 cannot supply current in this direction, so that an additional current sink must be provided to provide the negative resistance or current toward the summing point 25. This circuit will be explained in connection with FIGURE 4. In the above table, R_2 , R_4 , R_5 , R_7 , R_{11} , and R_{12} have magnitudes so large that they may be ignored. Hence, a current sink providing positive types of resistors R_1 , R_8 , and R_{14} is needed, and a current sink providing negative types of resistors R_3 , R_6 , R_9 , R_{10} , and R_{13} is needed. The circuit of these current sinks is shown 30 in FIGURE 4.

In FIGURE 4, circuit elements corresponding to the elements in FIGURE 3 have been given the same reference numeral or legend, or the same reference numeral or legend followed by the letter n to indicate its negative 35 resistance function. In FIGURE 4, the transistors Q_1 , Q_8 , and Q_{14} and associated circuit elements would be connected between the reference bus 11 and the negative bus 14, but only the transistors Q_1 and Q_{14} and their associated circuit elements have been shown in the interest of clarity. In the negative resistor portion of the current sink 26, an amplifier $18n$ has one input connected to the summing point 25. The feedback input is connected to a voltage divider comprising two resistors 40, 41 connected between an output bus $21n$ and the negative bus 14. The amplifier $18n$ has its output coupled through a resistor $19n$ to a 40 closed loop regulating circuit having two transistors Q_{An} and Q_{Bn} . The emitter of the transistor Q_{An} is connected to the output bus $21n$. By this circuit, the voltage V_{csn} across the negative portion of the current sink is kept equal to the voltage V_{cs} across the other portion of the current sink. The transistors Q_3 , Q_6 , Q_9 , Q_{10} , and Q_{13} and associated circuit elements would be connected between the output bus $21n$, and/or the positive bus 12, and the feedback input of the amplifier $18n$, but only the transistors Q_3 and Q_{13} and their associated circuit elements have been shown in the interest of clarity. In FIGURE 4, it will be noted that the potentiometers for the transistors have been replaced by voltage reference or Zener diodes Z and resistors R_Z . The Zener diodes Z and resistors R_Z are indicated by the letters followed by a number corresponding to the associated transistor number. The resistors R_Z and the Zener diodes Z are selected to determine the maximum current magnitude which their respective transistors Q may conduct in the same manner as the potentiometers P . If a transistor Q attempts to conduct more current, its emitter resistor R tends to bias or turn the transistor off. The values for the emitter resistors R were calculated by first selecting the voltage level for the Zener diodes Z , and then determining the value of the resistance R which would limit the current through the respective transistor Q to the desired magnitude. In the negative portion of the current sink 26, it will be seen that the transistors Q_3 and Q_{13} , as well as the other negative resistance transistors Q_6 , Q_9 , and Q_{10} (not shown), supply current toward the 70

summing point 25. Thus, their respective resistors R_3 and R_{13} , and resistors R_6 , R_9 , and R_{10} (not shown), present a negative value to the circuit and provide the desired output voltage V_o .

It will thus be seen that my invention provides an improved function generator for producing an output signal which has specified output magnitudes at specified points or steps relative to an input signal. This circuit is provided by a closed loop series type of regulator having a current sink in the feedback network, and permits the output signal to have almost any specified shape or magnitude at specified points. Persons skilled in the art will appreciate that modifications may be made. Almost any desired type of input signal may be tracked at any desired points to produce an output signal having selected magnitudes at these points. Various circuit voltages may be used, and other types of semiconductors and base control circuits may also be used. Therefore, while my invention has been described with reference to particular embodiments, it is 15 to be understood that modifications may be made without departing from the spirit of the invention.

What I claim as new and desire to secure by Letters Patent of the United States is:

1. A circuit for converting n specified input signal magnitudes into n specified output signal magnitudes respectively, where n is an integer greater than two, comprising:

- current control means having a control input, a feedback input, and a controlled output;
- means for applying said input signal to said control input;
- means connecting said controlled output to said feedback input for applying a feedback signal to said feedback input, said feedback signal varying as a function of an output signal at said controlled output;
- and a current flow path connected to said connecting means for providing a current flow that varies as a predetermined function of said feedback signal, and thereby changes said output signal at said controlled output to one of said n specified magnitudes when said input signal is at the corresponding one of said n input magnitudes.

2. The circuit of claim 1 wherein said current flow path provides a current flow in only one direction relative to said connecting means.

3. The circuit of claim 1 wherein said current flow path provides a current flow in both directions relative to said connecting means.

4. A function generator for converting an input signal to an output signal having n specified magnitudes for n specified points with respect to said input signal, where n is an integer greater than two, comprising:

- a closed loop series regulator circuit having an input circuit for said input signal, an output circuit for said output signal, a feedback input, and a feedback circuit connected between said output circuit and said feedback input;
- and a current sink connected to said feedback circuit, said current sink comprising n parallel current paths, each of said paths limiting the current magnitudes therethrough at a respective specified voltage at said feedback input.

5. The function generator of claim 4 wherein said current paths supply current in one direction relative to said feedback circuit.

6. The function generator of claim 4 wherein said current sink comprises a second plurality of parallel current paths limiting the current magnitude therethrough at a respective specified voltage at said feedback input.

7. The function generator of claim 6 wherein said first plurality of parallel current paths supplies current in a first direction relative to said feedback circuit and wherein said second plurality of parallel current paths supplies current in a second direction relative to said feedback circuit that opposes said first direction.

8. The circuit of claim 1 wherein said output signal is continuous but unspecified between adjacent ones of said n specified magnitudes.
